TIRE

Miles F. Morstatter, Akron, Ohio, assignor to The B. F. Goodrich Company, New York, N.Y., a corporation of New York

Filed Mar. 20, 1968, Ser. No. 11,058

Term of patent 14 years

Int. Cl. D12—14

U.S. Cl. D90—20

FIG. 1

FIG. 2

FIG. 1 is a fragmentary plan view of a tire showing my design, it being understood that the design is repeated about the entire circumference of the tire, the tire outline being indicated by broken lines; and

FIG. 2 is a sectional view taken substantially on the line 2—2 of FIG. 1, the tire outline being indicated, in part, by broken lines.

The dominant features of my design reside in the portions shown in solid lines.

I claim:

The ornamental design for a tire, substantially as shown and described.
